UNITED STATES PATENT OFFICE.

EDWARD A. HOEHN, OF DAYTON, OHIO, ASSIGNOR TO THE DAYTON HARDWARE SPECIALTY COMPANY, OF DAYTON, OHIO, A CORPORATION OF OHIO.

RESIDENCE MAIL BOX.

Application filed February 1, 1922. Serial No. 533,344.

To all whom it may concern:

Be it known that I, EDWARD A. HOEHN, a citizen of the United States, residing at Dayton, in the county of Montgomery and State of Ohio, have invented certain new and useful Improvements in Residence Mail Boxes, of which the following is a specification.

My invention relates to mail receptacles or safety deposit boxes for insertion within the wall of dwellings or other buildings, particularly after the completion of such buildings.

The invention contemplates the collapsible box or receptacle capable of being inserted within the intermediate air space between the outer weather boarding and the inner plaster wall of a building structure. The particular feature being its capability of being inserted through a comparatively small opening to subsequently serve as an access opening to the deposit box, and then being expanded or extended within the wall to a comparatively large capacity.

The object of the invention is to simplify the structure as well as the means and mode of application of wall contained mail receptacles and safety deposit boxes, whereby they will not only be cheapened in construction, but will be more efficient in use, of comparatively large capacity, and capable of being easily and quickly applied to existing building structures without disfigurement of the walls or necessity for providing an opening larger than would be required for the ordinary access opening.

A further object of the invention is to provide improved means for securing such receptacles or deposit boxes within the inner space of the building wall and to further provide in such a structure a reasonable range of variation of size which will accommodate it to inaccuracies of mechanical construction of the building and various thicknesses of the wall.

With the above primary and other incidental objects in view as will more fully appear in the specification, the invention consists of the features of construction, the parts and combinations thereof and the mode of operation or their equivalents as hereinafter described and set forth in the claims.

Referring to the drawings, Fig. 1 is a sectional perspective view of the mail recep-

tacle or safety deposit box forming the subject matter hereof applied within the intermediate air space of a frame structure wall. Fig. 2 is a like perspective view of the receptacle or box in its collapsed condition, but inserted within the wall through the access opening, preparatory to be expanded, upwardly to its maximum capacity. Fig. 3 is a detail perspective view of the relatively adjustable receptacle unit removed from the wall and separated one from the other, when viewed from the deposit side. Fig. 4 is a similar view of the receptacle unit, from the inner or access side. Fig. 5 is a detail vertical sectional view illustrating the manner in which the box is secured to the outer wall.

Like parts are indicated by similar characters of reference throughout the several views.

Referring to the accompanying drawings, wherein is shown the preferred, but obviously not necessarily the only form of embodiment of the invention, 1 represents the outer weather boarding and 2 the inner or lath and plaster wall of a frame building structure, of which 3 is the upright studding. The main receptacle or safety deposit box forming the subject matter hereof is adapted to be positioned within the air space between the weather boarding and plaster wall, which space is usually about four inches in depth, the depth being equal to the width of the standard studding 3. The present structure is capable of being inserted within this air space through a comparatively small access opening, cut in the inner or lath and plaster wall 2. In the present instance, the structure has been illustrated as a mail receptacle having a deposit slot for mail opening through the weather boarding 1 to the exterior of the building. It will be understood that in lieu of the upwardly extending receptacle, having the outwardly opening deposit slot as shown in the drawing, the structure may be downturned and no deposit slot provided when the structure is to be employed as a safety deposit box. Furthermore, while the structure has been shown applied to a frame building wall, it will be understood that it may be applied to hollow brick walls or walls of hollow tile, cement block constructions, or others having therein the usual intermediate air space.

In the present instance the receptacle or

container comprises two relatively adjustable telescopic units 4 and 5. The lower or primary unit 4 comprises a back section and upstanding side walls, and a bottom, but is devoid of a top and front wall. The telescopic or adjustable section 5 includes front, back and side walls, as well as a top section, but has no bottom. The dimensions of the telescopic section 5 are such that it is capable of being contained within the dimensions of the principal section 4, as is shown in Fig. 2. An access opening 6 is cut in the inner or lath and plaster wall 2, of sufficient dimensions to permit the insertion of the lower or principal receptacle section 4. A suitable slot 7 is cut in the outer wall or weather boarding 1, somewhat above the level of the access opening 6. The telescopic or upper unit 5 is provided in its outer wall 20 with parallel vertical slits 8 intersected by a transverse slit 9 to form two adjacent flaps 10. This unit 5 is inserted within the principal unit 4 with this cut portion or wall adjacent to the backs of the primary unit 4. The latter is then inserted within the access opening 6 formed in the inner wall 2 of the building structure, with its open side inwardly, and its closed back adjacent to the weather boarding 1. After being inserted 30 in place the margins of the side walls and bottom of the section 4 are bent or flanged outwardly as at 11, to overhang the edges of the access opening 6 and assist in securing the unit in place. The unit is constructed of ample horizontal depth to accommodate it to the deepest air space to which it may be applied. The degree of overhang of the margins of the side walls and bottom will depend somewhat upon the depth of the 40 air space. This construction affords a limited range of flexibility or adjustability to accommodate it to varying structural conditions. The primary unit 4 being in place the telescopic unit 5 positioned therein, the operator may then grasp the lower edge of the telescopic unit 5 and slidingly adjust the latter upwardly within the air space of the building wall to a position extending a considerable distance above the level of the access opening 6 until the flaps 10 formed in the back of the unit 5 are adjusted into registry with the deposit slot 7. These flaps 10 are then bent outwardly through the deposit slot and flanged in opposite direction 50 as shown in Fig. 1 to secure the upper adjustable unit in its extended position. To further secure the units 4 and 5 in position nails or screw 12 may then be inserted through the access opening 6 in the backs of the respective units, by which they may be secured to the weather boarding 1. The lower edge of the front or inner wall of the unit 5 is then preferably bent outwardly and upwardly as indicated at 13 about the upper 60 edge of the access opening 6. The extent of

the overhang of this flange will of course depend upon the relative adjustment of the member 5 within the air space. The units having been relatively adjusted or expanded within the air space of the wall and secured in their adjusted position, a letter slot closure plate 14 having the usual swinging closure 15 may be applied to the outside of the weather boarding 1 over the slot 7 as shown in Fig. 1. A suitable frame 16 of ornamental or pleasing character having therein an access door 17 is applied to the inner wall 2 over the access opening 6. For convenience, this door 17 may comprise a stack having therein an observation flask 18 through which the contents of the receptacle may be observed. It may be provided with a lock. Mail may be deposited through the deposit slot 7 from the outside of the building into the receptacle from which it can be removed by the occupant through the access door 17 without going outside.

While the device has been shown of comparatively small size for the reception of the ordinary household mail, it will be understood that it may be constructed of larger size for use as a parcel or package receiver, and as before mentioned the deposit slot may be omitted, and the structure employed as a safety deposit box, either up-turned as shown in the drawings, or in an inverted position, wherein the adjustable section will extend downwardly from the access opening. Inasmuch as such construction would involve no structural change whatsoever, and the same mode of application would be employed, it is not thought necessary to illustrate this variation.

The construction is such that it may be conveniently and quickly applied to an ordinary existing dwelling or other building structure by a mechanic of ordinary skill, without marring or damaging the walls nor requiring an opening larger than the ultimate access opening necessary for the removal of the contents.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is therefore

claimed in any of its forms or modifications within the legitimate and valid scope of the appended claims.

Having thus described my invention, I 5 claim:

1. In a construction of the character described, the combination with a hollow wall having in one side thereof a deposit slot and in the other side thereof an access opening 10 at a lower level, of an expansible receptacle insertable within the interior of the hollow wall through said access opening and capable of being subsequently extended within the wall to a point beyond said deposit slot.
- 15 2. As an article of manufacture, an expansible deposit box insertable within a hollow wall structure through a comparatively small access opening when in collapsed condition and subsequently expanded within 20 the hollow wall beyond the confines of said access opening.
- 25 3. In a construction of the character described, a hollow wall, a deposit box within the hollow wall, a deposit slot through the outside of the hollow wall into said deposit box; an access opening through the inner side of the hollow wall into said deposit box, said access opening being of less dimensions than the deposit box, said box consisting of 30 separable sections insertable within the wall through said reduced access opening.
- 35 4. As an article of manufacture, a deposit box insertable within a hollow wall comprising a plurality of separable sections insertable within the hollow wall through an access opening of comparatively small dimensions and subsequently positioned in extended association within the wall to form a deposit receptacle extending beyond the 40 confines of the access opening.
- 45 5. As an article of manufacture, a deposit box insertable within a hollow wall, comprising a plurality of telescopically arranged sections insertable within the wall while collapsed through a comparatively small access opening and subsequently extensible within the wall beyond the confines of said access opening.
- 50 6. As an article of manufacture a safety deposit box for insertion within a hollow wall comprising separable units slidably adjustable in relation one with the other, said sections when slidably adjusted one toward

the other being capable of insertion within a hollow wall through a small access opening, said units being capable of sliding adjustment one from the other within the wall to enlarge said box beyond the margins of the access opening.

7. In a construction of the character described, the combination with a hollow wall structure having an opening in one side thereof, of a receptacle insertable within the hollow wall, flexible flaps upon said receptacle adapted to be bent outwardly 65 through said opening subsequent to the insertion of the receptacle within the wall to secure the receptacle in fixed relation therewith.

8. In a construction of the character described, the combination with a hollow wall structure having an access opening therein, of a receptacle insertable within the interior of the wall through said access opening, 70 said receptacle having flexible flanges projecting through the access opening when the receptacle is inserted within the wall, said flanges being adapted to be clenched over the margins of the access opening, to retain the receptacle in fixed relation therewith.

9. As an article of manufacture, a receptacle unit having an open side and top and a second bottomless unit insertable within the first unit, said assembled units being insertable through an access opening in a 85 hollow wall into the interior thereof and subsequently extended therein by thrusting the second unit out of the first unit thru the open top thereof.

10. The herein described method of applying a deposit receptacle within a hollow wall consisting in forming in the side of the wall an access opening of less size than the maximum size of the receptacle, collapsing the receptacle inserting the collapsed receptacle within the interior of the wall through said access opening and subsequently expanding the collapsed receptacle, substantially as specified.

In testimony whereof, I have hereunto set 100 my hand this 14th day of January A. D. 1922.

EDWARD A. HOEHN.
